(57) **CLAIM**

The ornamental design for a docking station, as shown and described.

DESCRIPTION

FIG. 1 is a front, left, top perspective view of a docking station, showing the new design in a closed configuration; FIG. 2 is rear, right, bottom perspective view thereof; FIG. 3 is a top plan view thereof; FIG. 4 is a bottom plan view thereof; FIG. 5 is a left side view thereof; FIG. 6 is a right side view thereof; FIG. 7 is a front elevation view thereof; FIG. 8 is a rear elevation view thereof; FIG. 9 is a front, left, top perspective view of the docking station of FIG. 1, showing the new design in an open configuration; FIG. 10 is rear, right, bottom perspective view thereof; FIG. 11 is a top plan view thereof; FIG. 12 is a bottom plan view thereof; FIG. 13 is a left side view thereof; FIG. 14 is a right side view thereof; FIG. 15 is a front elevation view thereof; and, FIG. 16 is a rear elevation view thereof.

The broken lines of even length shown in the drawings illustrate portions of the docking station that form no part of the claimed design.

1 Claim, 16 Drawing Sheets
